WILLIAM H. HOVEY, OF SPRINGFIELD, MASSACHUSETTS.

Letters Patent No. 67,548, dated August 6, 1867.

IMPROVED BRICK MACHINE.

The Schedule referred to in these Letters Patent and making part of the same.

TO ALL WHOM IT MAY CONCERN:

Be it known that I, WILLIAM H. HOVEY, of Springfield, Hampden county, Commonwealth of Massachusetts, have invented certain new and useful improvements in Brick Machines; and I do hereby declare that the following is a full and exact description thereof, reference being had to the accompanying drawings and to the letters of reference marked thereon.

The drawings forming part of these specifications are arranged upon plates 1, 2, 3, and 4.

Figure 1, plate 1, represents a front view of my improved machine.

Figure 2, plate 2, a side view.

Figure 3, plate 3, a plan view of the under gearing.

Figures 4, 5, 6, 7, 8, detail views of parts of my invention on plate 4.

This invention consists of a new and improved arrangement of the brick machine patented by me February 16, 1866, some of the parts and principles of which I use, substituting improvements in the place of others.

In construction, I form my new machine upon a frame, A A, composed of suitable material, having a hopper, B, with crushers C C', through which the clay passes, and is ground fine; and a longer hopper, D, where the clay is received from the crushers C C', and worked up into the proper consistency for making brick. In the bottom of the hopper D are two openings E E', through which the clay falls into channels or chambers F F', in which work flanges G G', these latter forcing the clay that falls in the chambers F F' through the dies and out to the action of the knives H H and H' H', which cut the mass of clay so forced out into the proper lengths for brick. The device for working the clay in the hopper D consists of a main shaft, I, passing up vertically through the centre of the hopper D, and having set into it, at proper distances apart, arms or knives a a a, &c., which, as the shaft I revolves, stir up and work the clay. This is shown in fig. 4, plate 4, where is also shown my device for sweeping the ground clay into the channels F F', through the openings E E'. This consists of arms b b', set into the shaft I, and having teeth c c c, &c., set into them, at a suitable angle, between the horizontal and vertical. One of these, as the shaft I revolves, sweeps the clay into the chambers, through the openings, causing them to be more surely and evenly filled, the other performing a part shown hereafter. The plungers G G' work alternately, and are attached to and operated directly by a walking-beam, J, each end of which is connected with one of the plungers by means of connecting-rods K K'. The beam J is fastened at its centre upon a vertical shaft, T, working in bearings L L, at the back of the machine. A reciprocating motion is given to this shaft by means which I will now describe. At the lower end of the main shaft I is attached a large gear-wheel, M, which is operated by a pinion, N, upon a shaft, O, underneath the hopper. Now upon the vertical shaft T is a crank, P, which is placed under the walking-beam J. This crank fits loosely upon the shaft T, and has attached to its end a connecting-rod, R, having its other end pinned upon the lower side of the gear-wheel M, thus forming a crank that, when the wheel M revolves, works the arm g backwards and forwards. The crank-arm P can be attached to the shaft T by means of a clutch upon the same, consisting of a sleeve, d, which is movable up and down upon the shaft T, but cannot be turned upon it. This sleeve has a dog, f, at its top edge, which fits, when the sleeve is raised, into a notch or slot in the lower edge of the crank-rod P. The lower edge of the sleeve d has cam surfaces, which correspond with similar ones upon the top edge of a collar, e, also around the shaft J. These cam-teeth mesh in with each other in one position, allowing the sleeve d to slip down, leaving the shaft J and crank-arm P ungared, but by turning the collar e the sleeve d is elevated, and clutches the crank-arm P, connecting the same to the shaft T.

The object of this arrangement is to allow the grinding and working portion of the machine to act upon the clay, without the plungers operating to force it out into bricks before it has been brought to the proper consistency. This is usually necessary when the clay is first put into the hoppers. When the clay is forced through the channels F F' by the plungers, it has to pass through dies g g' before it is cut off by the knives. These dies I form in a peculiar shape, so as to cause the clay to move through at all parts with the same rapidity. This form is shown in figs. 5 and 6, plate 4, where it is seen that the front openings of the dies, where the clay comes out, are formed in a parallelogram, being the width and thickness of a brick. The rear openings of these, however, where the clay goes in, are oval in shape, and the four points forming the corners of the parallelogram in front, are found in the line of the oval, so that there is a taper from rear to front at all

parts except the corners. This is necessary in order that the clay should come out even and firm at the corners, for were the dies not formed in this manner the corners of the brick so made would be cracked and uneven.

The knives for cutting off the brick are operated by gearing arranged in the following manner: A bevelled gear-wheel, U, is attached to the top of the main shaft I, and operates a similar wheel set upon a shaft, V, running horizontally. Across the top of the machine, on the front end of the shaft V, are set two pulleys *i* and *j*, the one, *i*, operating two more pulleys *k* *k'*, upon the shafts *l* *l'*, having the knives H H and H' H' by means of a chain-gear, W, passing around them, and the one, *j*, a similar gearing which turns the grinders C C'. These pulleys are all of the same size, and are constructed in the form shown in fig. 7, plate 4, with projections 1, 2, 3, and 4, for the links of the chain to pull against. Each of the shafts *l* *l'* has a pair of knives, which are placed so upon the shafts that the edges of each pair as the shafts *l* *l'* revolve the knives, turn with them, passing, as they come around, through grooves *o* *o* *o* in the troughs *n* *n'*, along which the clay passes after coming through the formers. The gearing of the whole machine is arranged so as to be automatic, and these knives do not pass across the troughs *n* *n'* until the plunger of either side, as the case may be, has forced its load of clay out into its troughs, and left it there to be cut off, the knives only cutting while the clay is stationary, when the same operation is repeated in a similar manner on the other side.

The blades of the knives are arranged upon the hafts in such a manner as to allow them to give back should they meet any impenetrable obstruction in the clay, and so preventing them from being broken off or the machine clogged. The manner of so arranging these knives is shown in fig. 8, of plate 4, where the blade *p* is riveted at *q*, upon the haft *r*, the latter being attached firmly to the shaft *l*. A strong coil spring is attached to the haft by a screw, *s*, having the outer end of the coil attached to or resting against a pin, *t*, set in the blade of the knife. The blade is prevented from being forced forward by the spring, by means of a pin, *u*, set in the haft, and against which the projection *v* of the blade rests.

In fig. 4, plate 4, where two sweeps are shown, consisting of the arms *b* *b'*, with teeth *c* *c* *c*, &c., it is shown that only one of these sweeps operates directly to fill the openings in the bottom of the hopper, as by the automatic arrangement of parts one of the plungers is occupying its chamber immediately beneath the opening at the same time that one of the sweeps passes over it, so that one of these fills the chambers, while the other merely passes around and stirs up the clay, leaving it loose and ready for the operation of the other sweep.

The operation of this machine is as follows: The grinders C C', at the bottom of the hopper B, being adjusted as desired, by means of the set-screws W W, operating the sliding-bearings *x* *x*, of the grinder C', the clay is put into the hopper B, where it is ground fine and falls through into the hopper D, where it is worked up thoroughly by the arms on the shaft I. The plungers are then thrown into gear by the clutch, already described, and the clay is forced out through the dies in proper quantities at a time. As the clay comes out and remains in the troughs, the knives cut it into the proper lengths, and the bricks so formed are pushed out on the shelf in front of the troughs and taken off by the operator.

By altering the dies in various forms, any variety of shape can be given to the brick, and mouldings of any length produced, by ungearing the knives and allowing the clay to pass on without cutting it off. The superior arrangement of the machinery used in my device, and the excellent quality of the brick made by it, render it a great improvement in machines of this class.

Now, having described my invention, what I claim as new, and desire to secure by Letters Patent, is—

1. The combination of the lever-beam J, plungers G G', and connecting-rods K K', arranged and connected substantially as shown.

2. The combination and automatic arrangement of the parts as follows: The gear-wheel M, operating the crank-arm P, and main shaft I, the latter turning the shaft V, with its pulleys *i* and *j*, and chain-gear, operating the revolving knives H H H' H', and crushers C C', the whole substantially as shown.

3. One or more sweeps, consisting of the arms *b* *b'*, having teeth *c* *c* *c*, one of them operating automatically with the plungers, so that it fills the chambers alternately with clay, when the plunger of each chamber has receded in turn; this or these in combination with the plungers G and G'.

4. I claim the peculiar shape of the dies *g* *g'*, so that they taper from an ellipse to a parallelogram, the width and thickness of the brick desired, tapering at the sides, but not at the corners, substantially as shown.

5. Arranging the plungers G G', so that they may be thrown out of gear, allowing the clay to be ground and worked, but not pressed into brick.

6. The revolving knives H H H' H', in combination with the troughs *n* *n'*, having the grooves *o* *o* *o*, arranged substantially as shown.

WM. H. HOVEY.
